FASTENING INSERTING MACHINE

Fred N. La Chapelle, Beverly, Mass., assignor to
 United Shoe Machinery Corporation, Paterson,
 N. J., a corporation of New Jersey

Application August 25, 1930, Serial No. 477,632

36 Claims. (Cl. 1—30)

This invention relates to fastening inserting machines used in the manufacture of boots and shoes and is herein illustrated as embodied in a machine of the type disclosed in United States Letters Patent No. 1,802,900, granted April 28, 1931, on an application filed in the names of Fred N. La Chapelle and Fred C. Eastman, though it is to be understood that the invention is not limited to embodiment in machines of this type.

The machine of the Letters Patent referred to above, is particularly adapted to insert fibre pegs through shoe parts and to head the fastenings to secure the shoe parts firmly together. In the operation of the machine illustrated in said application the fastenings are inserted through the work and headed in such a way that their heads project somewhat above the surface of the work. In certain operations, however, in the manufacture of boots and shoes, for example in securing a shank stiffener to the sole of a turn shoe, it is desirable to head the fastenings flush with the surface of the work in order to obtain a smooth surface on the inside of the shoe without sacrificing any of the advantages of a headed fastening.

It is, therefore, an object of the present invention to provide a fastening inserting machine by the use of which fibre fastenings, for example, may be headed flush with the surface of the work.

More particularly, the invention aims to provide a fastening inserting machine especially adapted to insert fibre fastenings such as paper pegs in fastening receiving holes and to head the fastenings in enlarged or countersunk portions of the holes.

In view of the foregoing, and in accordance with features of the invention, the illustrated fastening forming and inserting machine is provided with a reciprocated sleeve the lower end of which is conical and is utilized to counter-sink or enlarge the entrances of the fastening receiving holes formed by an operating tool which is reciprocated through a passage in the sleeve in timed relation with the reciprocation of the sleeve and which acts first to form a fastening receiving hole in a work piece presented to the machine and then, after the reciprocating sleeve has enlarged the entrance of the hole, to insert a fastening in the hole and to head the fastening in the enlarged entrance.

The above and other objects and features will appear from the following description read in connection with the accompanying drawings.

In the drawings,

Fig. 1 is a view in side elevation of a portion

of a fastening inserting machine embodying the invention;

Fig. 2 is an enlarged view of a portion of the head of the machine;

Fig. 3 is a section taken on the line III—III of Fig. 2;

Fig. 4 is a section taken on the line IV—IV of Fig. 2;

Fig. 5 is a cross-sectional view of the work showing a tool which acts both as an awl and, after the completion of its awl stroke, as a driver;

Fig. 6 is a view similar to Fig. 5 showing a counter-sinking sleeve in operative position;

Fig. 7 is a view similar to Fig. 5 showing the tool of Fig. 5 at the completion of its fastening inserting stroke;

Fig. 8 is a detail view of stroke adjusting mechanism of the tool of Fig. 5; and

Fig. 9 is a detail view of the driver bar of the machine.

Referring to the drawings which show a machine embodying a preferred form of the invention, 10 (Fig. 1) designates a base or standard which supports the head 12 having mounted therein a shaft 16 provided with a loose pulley 19. The rotation of the shaft 16 is controlled by a stopping and starting mechanism comprising a clutch member 22 and a brake member 24 controlled by a treadle (not shown). The stopping and starting mechanism may be and as illustrated is substantially the same as that shown in United States Letters Patent No. 1,691,130 granted Nov. 13, 1928, on the application of John B. Roulo. The horn 20 is raised by depression of the treadle and is held in raised position during one cycle of operation of the machine by connections from the stopping and starting mechanism and is then released.

Fast on the shaft 16 is a group of cams preferably formed as a unit and hereinafter designated as a cam member and indicated generally by the numeral 18. The illustrated machine is provided with a tool 30 arranged to operate both as an awl and as a driver. The tool 30 is clamped at 31 (Fig. 9) to a tool carrier 32 mounted for vertical reciprocation in a guideway 34 carried by or formed in the head 12 of the machine.

The mechanism for giving the tool 30 its awl stroke and its driver stroke includes a lever 42 fulcrumed at 44 to the head of the machine and having two parallel arms pivoted at their rear ends to a link 46 (Figs. 1 and 8) positioned approximately vertically and having a pivoted bearing at its lower end in a slot 48 formed in

a rearwardly extending arm of a bell crank lever 50 fulcrumed at 52 to the head of the machine and having an upwardly extending arc 54 carrying a cam roll 56 positioned in a cam track 58 formed in the cam member 18. The slot 48 is formed on an arm of a circle having a radius equal to the distance between the pivots of the link 46 and positioned concentric with a pivotal connection between the link 46 and the lever 42 at the time the tool 30 makes its driving stroke. Means illustrated as a spring-plunger 59 is provided for preventing undesired movement of the link 46 lengthwise of the slot 48. The position of the link 46 in the slot 48 may be varied to increase or decrease the length of stroke of the tool 30 when it acts as an awl to provide for differences in the thickness of different work pieces. The adjustment is facilitated by a handle formed as a part of or secured to the lower end of the link 46. The position of the link 46 may also be adjusted so that the tool 30 does not entirely penetrate the work because it is often desirable to conceal a fastening on an exposed surface such for example as the shank portion of a shoe. It will be seen that the rocking movement imparted to the bell crank lever 50 by the cam track 58 operates cyclically to rock the lever 42 up and down about its fulcrum 44. The form of the cam slot 58 is such as to position the lever 42 in its uppermost position early in the cycle of operation when the tool 30 is operating as an awl and to position the lever 42 in its lowermost position later in the cycle when the tool is operating as a driver.

Fulcrumed at 60 to the lever 42 is another lever 62 having at its forward end a link 63 which is pivotally connected at its other end to the tool carrier 32. A stiff coil spring 64 surrounds the fulcrum 60 of the lever 62 and is anchored at one end to a disk 66 arranged to be adjustably secured to the lever 42 by a pin 68. At its other end the spring 64 is secured to a housing secured to or formed as a part of the lever 62. Thus the spring 64 tends at all times to rock the lever 62 in a counterclockwise direction as viewed in Fig. 1 and to urge the tool carrier 32 and the tool 30 downwardly.

At its forward end the cam member 18 is provided with a lifting cam 70 having a pair of elevated portions. Mounted for vertical sliding movement in the head 12 of the machine is a lifting bar 72, the lower end of which bears against the cam 70 and thus serves as a lifting block. Pivotied to the lifting bar 72 is a block 74 positioned in a slot 76 formed in the lever 62. Thus as the cam member 18 rotates, the lifting bar 72 is elevated by the cam 70, the spring 64 being correspondingly compressed. Then when one of the elevated portions of the cam 70 passes out from beneath the lower end of the lifting bar 72, the spring 64 forces the lifting bar 72 and the lifting block 74 downwardly, thus rocking the lever 62 in a counterclockwise direction and forces the tool carrier 32 and the tool 30 downwardly. A bumper 78 clamped on the upper end of the lifting bar 72 impinges on a boss 80, thus limiting the downward stroke of the lifting bar 72.

In the illustrated machine, one portion of the cam 72 passes out from beneath the lifting bar 72 when the fulcrum 60 of the lever 72 is in its uppermost position, the tool 30 then being forced downwardly through a nozzle 82 and into the work to form a fastening receiving hole. The nozzle 82 is several inches long so that its lower end may engage a shank piece to be fastened

inside a turn shoe. When the shaft 16 has been rotated through another 180 degrees and the other elevated portion of the cam 70 has raised the lifting bar 72 and passed out from beneath the lifting bar, the fulcrum 60 of the lever 62 has been moved to its lowermost position, so that the downward movement of the tool carrier 32 and the tool 30 is only sufficient to drive the fastening which at that time has been brought into alignment with the throat opening of the nozzle 82 and with the tool 30. In order that the two strokes of the tool 30 though terminating at different points may be approximately of the same length, one elevated portion of the cam 70 is somewhat higher than the other elevated portion.

The mechanism for countersinking or enlarging the entrance for the fastening receiving hole will now be described. Secured to the shaft 16 is a cam 86 (Figs. 1, 2, 3 and 4) which acts against a cam roll 88 to move the arm 90 of a bell crank lever 91 in a clockwise direction as viewed from the front of the machine in Figs. 3 and 4. The bell crank 91 is journaled to the machine head by means of a pin 92 (Fig. 4) and the cam roller 88 is held against the cam 86 by means of a suitable spring 94. The lower arm of the bell crank 91 is formed with teeth 96 which mesh with teeth 98 formed on a collar 100 which in turn is clamped to one end of a shaft 102 by means of a stud 104. The shaft 102 is journaled in a bearing 106 formed in the head of the machine. Formed at the other end of the shaft 102 is a collar 108 having teeth 110 which mesh with teeth 112 secured to or formed as a part of a sleeve carrying member 114 which carries at its lower end a sleeve 116. The sleeve carrier 114 has at its upper end a tool guide 117 through which the tool 30 passes and the sleeve carrier 114 and the sleeve 116 have a passage 118 through which the tool 30 reciprocates. Rotation of the shaft 16 causes the high part 87 of the cam 86 to swing the arm 91 in a clockwise direction which, through the connections above described, causes the sleeve 116 to be moved downwardly from the position shown in Fig. 5 to the position shown in Fig. 6 so that the conical lower end of the sleeve countersinks or enlarges the entrance to the fastening receiving hole which has previously been formed by the tool 30 and forms an enlarged entrance for a fastening receiving hole. A fastening 122 is thereafter inserted and headed in the enlarged entrance to the hole as hereinafter described.

The paper twine from which the fibre pegs inserted by the illustrated machine are cut, is carried by a reel 128 (Fig. 1) rotatably mounted upon the head 12 of the machine. The twine passes from the reel 128 to a tubular guide member 130 mounted for vertical reciprocating movement at the front of the head of the machine. Means for engaging the twine and feeding it downwardly with the downward movement of the guide 130 and for preventing retrograde movement of the twine 126 is indicated generally by the numeral 132. The twine feeding and measuring mechanism is substantially as shown in the above-mentioned copending application Serial No. 202,416 to which reference may be had for a more detailed description of the twine feeding mechanism.

The tube 134 conducts the strip of fastening material to an opening 136 formed in a shear bar 137 secured at the forward end of a rod 138 mounted for endwise sliding movement in a guide 75

formed in the head 12 of the machine and clamped as shown at 140 in Fig. 1 to a rod 142. Cooperating with the shear bar 137 is another shear member or block at the lower extremity of the tube 134. Thus it will be seen that early in the cycle of operation as the rod 138 is moved forwardly by the cam 144 a fibre peg will be severed from a strip of fastening material 126 and carried forward into the line of drive of the tool 30.

10 The length of each fastening formed is determined by adjustment of a rod 158 in slots 166 and 168 as will now be described. Pivoted at 146 to the guide member 130 is a link 148 (Fig. 1) the other end of which is pivoted at 150 to the forward end of a bell crank lever 152 fulcrumed at 154 to the head 12 of the machine and having a depending arm 156 pivoted to the approximately horizontal link 158, the rear end of which is pivoted to the depending arm of a bell crank lever 160 fulcrumed on the head 12. A forwardly extending arm 162 of the bell crank lever 160 is pivotally secured at 164 to a link 165 which in turn is connected to the lever 42. The lower arms 156 and 160 are provided with slots 166 and 168 into which are pivotally secured the ends of the rod 158. Adjustment of the rod 158 in these slots varies the relation of the length of the fastenings to the depth of the holes formed in the work piece.

20 While the operation of the various parts of the machine has already been described, it may be helpful to consider now the operation of the machine as a whole. With the parts of the machine in the position shown in Fig. 1, the work in which fastenings are to be inserted, for example, the shank portion of a turned shoe, is presented by the operator to the nozzle 82 properly to locate the same relatively to a hole formed in the shank stiffener 170. The operator then depresses the treadle, thus raising the horn 172 so that the work is held securely against the nozzle. The upper end of the horn is provided with a leather insert to prevent marking of the outsole of the shoe operated upon. The movement of the treadle releases the brake and throws the clutch into operation thus rotating the shaft 16 of the machine. The rotation of the shaft 16 then causes the cam 70 to lift the bar 72 and also the lever 62 and when the lower of the two high parts of the cam 50 passes out from under the lifting bar 72 the tool 30 moves downwardly to pierce the work to form a fastening receiving hole in the filler piece 174 and the sole 176. The sleeve 116 is then forced downwardly into the position shown in Fig. 6 to form an enlarged or countersunk entrance to the fastening receiving hole in the filler piece 174. Further movement of the cam shaft causes the tool 30 to be withdrawn from the work and the sleeve 116 to be returned to its original position, as shown in Fig. 3. The lever 42 is then brought to its lowermost position by means of the bell crank 50 through the link 46 and the tool 30 is now in its fastening inserting position. At the same time, the strip of fastening material 126 is fed downwardly into the hole 136 formed in the shear bar 137. The slide 138 is then moved to the left by the action of the cam track 144 upon the cam roll 142, thus shearing a fastening and positioning it in the path of movement of the tool 30. The lifter bar 72 then moves downwardly under the impulse of the spring 64 to insert the fastening and head it in the countersunk entrance formed in the filler piece 174 by the sleeve 116, thus completing the cycle of operation of the machine. The machine is then automati-

cally stopped with the parts in the position shown in Fig. 1.

Having thus described my invention what I claim as new and desire to secure by Letters Patent of the United States is:

5 1. In a fastening inserting machine, means for forming fastening receiving holes in a work piece, independently operated means for enlarging the entrances of the fastening receiving holes, and means for inserting fastenings in the holes 10 and for heading the fastenings in the enlarged entrances of the holes.

15 2. In a fastening inserting machine, means for forming a fastening receiving hole, means movable relatively to said hole forming means for enlarging the entrance to the hole, and means for inserting a fastening in the hole and heading the fastening in the enlarged entrance of the hole.

20 3. A fastening inserting machine having, in combination, means for forming a fastening receiving hole in a work piece, and means for enlarging the entrance of the fastening receiving hole, said hole forming means acting also to insert a fastening in the hole and to head the fastening in the enlarged entrance of the hole.

25 4. A fastening inserting machine having a single means for forming fastening receiving holes in a work piece and for inserting fastenings in said holes, and means for enlarging the entrances of the fastening receiving holes, the fastening inserting means being constructed and arranged to head the fastenings in the enlarged entrances to the holes.

30 5. A fastening inserting machine having an awl, means for operating said awl to form fastening receiving holes in a work piece, reciprocating means operating independently of the hole forming means for enlarging the entrances of the fastening receiving holes, and means for inserting fastenings in the holes and heading them in the enlarged entrances.

35 6. A fastening inserting machine having a tool for forming fastening receiving holes in a work piece and for inserting fastenings in such holes, and cam operated means separate from the hole forming means constructed and arranged to enlarge the entrances of the fastening receiving holes.

40 7. In a fastening inserting machine, a drive shaft, a fastening inserting instrumentality for inserting and heading a fastening in a fastening receiving hole, means carried by the drive shaft for imparting operating movements to the fastening inserting instrumentality, means for forming a fastening receiving hole, a member for enlarging the entrance of the fastening receiving hole to provide for the heading of a fastening in the hole, and cam operated means separate from the fastening inserting instrumentalities for imparting reciprocating movement to the member.

45 8. In a fastening forming and inserting machine, means for forming fastenings, a member for forming fastening receiving holes in a work piece for inserting and for heading the fastenings in the holes, and means for enlarging the entrances of the fastening receiving holes to provide for the heading of the fastenings in the holes.

50 9. In a fastening inserting machine, means for forming headless fastenings, means for forming fastening receiving holes, means movable relatively to the hole forming means for enlarging the entrance of said fastening receiving holes, and means for inserting the fastenings in the holes.

and for heading the fastenings in the enlarged entrances of the holes.

10. In a fastening inserting machine, means for forming headless fastenings, means for forming fastening receiving holes in a work piece, and means for enlarging the entrances of the fastening receiving holes, said hole forming means operating also to insert the fastenings in the holes and to head them in the enlarged entrances of the holes.
- 10 11. In a fastening inserting machine, means for severing fastenings from a strip of fastening material and feeding the fastenings into the path of a fastening inserting tool, a tool for forming fastening receiving holes in a work piece and for inserting the fastenings and heading them in the holes, and means for enlarging the entrances of the holes to receive the headed ends of the fastenings.
- 15 12. In a fastening inserting machine, a tool operating both as an awl and as a driver, means for feeding a fastening into the path of movement of the tool, and a sleeve operated by a cam to enlarge the entrance of a fastening receiving hole formed by the tool, said tool operating also to head the fastening in the enlarged entrance of the hole.
- 20 13. In a fastening inserting machine, fastening forming and inserting instrumentalities including a tool for forming a fastening receiving hole and a cam-operated reciprocating sleeve having a conical lower end operating independently of said tool to enlarge the entrances to the holes formed by said tool, said fastening inserting instrumentalities being constructed and arranged to head the fastenings in the enlarged entrances of the holes.
- 25 14. In a fastening inserting machine, means for forming a fastening receiving hole, a cam, a sleeve for forming a countersink in a work piece, and connections between the cam and the sleeve to impart movement to the sleeve to move it toward and from the work piece and relatively to the hole forming means.
- 30 15. In a fastening forming and inserting machine, means for forming fastening receiving holes in a work piece and for inserting fastenings in the holes, means for forming headless fastenings, and cam operated means for enlarging the entrances of the fastening receiving holes to facilitate heading of the fastenings in the holes.
- 35 16. In a fastening forming and inserting machine, means for forming and feeding headless fastenings into the path of movement of a fastening inserting instrumentality, means for forming fastening receiving holes in a work piece presented to the machine, a reciprocating sleeve formed and arranged to enlarge the entrances of the fastening receiving holes, and means for inserting and heading the fastenings in the enlarged entrances.
- 40 17. In a fastening forming and inserting machine, the combination of fastening forming instrumentalities, means for forming a fastening receiving hole, a sleeve surrounding said means and constructed and arranged to reciprocate independently of the hole forming means to form an enlarged entrance for the fastening receiving hole, and means for inserting a fastening in the hole and heading it in the enlarged entrance of the hole.
- 45 18. In a fastening forming and inserting machine, the combination of fastening inserting and forming instrumentalities with cam operated means for forming a fastening receiving hole, a sleeve operating independently of said hole forming means to form an enlarged entrance for said
- 50 hole, the fastening inserting means being constructed and arranged to head a fastening in the enlarged entrance to the hole.
- 55 19. In a fastening inserting machine, a nozzle, means for forming a fastening receiving hole, a sleeve in said nozzle operating independently of said means for enlarging the entrance of a fastening receiving hole, and means for inserting and heading a fastening in said hole.
- 60 20. In a fastening inserting machine, a nozzle having a passage, means for forming fastening receiving holes in a work piece constructed and arranged also to insert fastenings in said holes, and a sleeve in the nozzle passage for enlarging the entrance of the holes so that fastenings may be headed in the enlarged entrances.
- 65 21. In a fastening inserting machine, the combination of a nozzle having a passage therethrough, a sleeve constructed and arranged to be reciprocated within said passage, means reciprocating in said sleeve for forming fastening receiving holes in a work piece and for inserting a fastening in said holes, and means for reciprocating said sleeve to form a countersunk entrance to the fastening receiving hole in the work piece.
- 70 22. In a fastening inserting machine, means for forming fastenings, means for forming a fastening receiving hole in a work piece, a sleeve having a lower conical end for enlarging the entrance of the hole, said sleeve being constructed and arranged to reciprocate relatively to said hole forming means, and means for inserting and heading a fastening in the hole.
- 75 23. A machine having means for forming headless fastenings, means for forming a fastening receiving hole in a work piece, means for feeding the fastening into alignment with the hole, and means for enlarging the entrance of the hole, said first-mentioned means being constructed and arranged to insert a fastening in the hole, and also to head the fastening in the enlarged entrance of the hole.
- 80 24. In a machine for forming and inserting fastenings, fastening inserting means, means for forming headless fastenings and feeding them into the path of movement of the inserting means, and a reciprocating sleeve for countersinking a hole in the work into which the fastenings are inserted and headed by the fastening inserting means.
- 85 25. In a fastening forming and inserting machine, reciprocating means for forming fastening receiving holes in a work piece, means reciprocating independently of said hole forming means for countersinking the entrances to the holes, means for forming headless fastenings, and a driver for inserting the fastenings into the holes and heading them in the countersunk entrances to the holes.
- 90 26. In a fastening inserting machine, means for forming headless fastenings, means for forming fastening receiving holes in a work piece, means movable relatively to said hole forming means for enlarging the entrances of the holes, and means for driving the fastenings into the holes and heading them in the enlarged entrances.
- 95 27. In a fastening inserting machine, means for forming headless fastenings, means for forming fastening receiving holes in a work piece, and for inserting fastenings in such holes, and means for countersinking the entrances of the holes, the means for inserting the fastenings in the holes operating also to head them in the countersunk entrances to the holes.
- 75 28. In a fastening inserting machine, means

for forming a fastening receiving hole, said means being constructed and arranged also to insert a fastening in the hole, a sleeve having a conical lower end, and means for reciprocating the sleeve 5 to cause the lower end of the sleeve to form a countersunk entrance for the fastening receiving hole.

29. In a fastening inserting machine, a reciprocating sleeve, an operating tool reciprocating in 10 a passage in the sleeve, means for reciprocating the operating tool, and means for causing the sleeve to reciprocate in timed relation to the operating tool to enlarge the entrance of a hole formed by the tool.

15 30. In a fastening inserting machine, a tool for forming a fastening receiving hole and for inserting a fastening in the hole, and a sleeve having a passage through which the hole forming and inserting means reciprocates, said sleeve 20 being constructed and arranged to reciprocate to form a conical entrance for the fastening receiving hole after the tool has performed its hole-forming operation.

31. In a fastening inserting machine, means 25 for forming fastening receiving holes and inserting fastenings in the holes, a reciprocating sleeve for countersinking the entrance of the hole, a cam, and connections between the reciprocating sleeve and the cam for causing the sleeve to 30 reciprocate to perform its countersinking operation.

32. In a fastening inserting machine, an operating tool for forming a fastening receiving hole and for inserting a fastening in the hole, a sleeve 35 having a passage through which the operating tool reciprocates to perform its operations, said sleeve having a conical lower end, and means for reciprocating the sleeve to enlarge the entrance of the hole in which the fastening is to be inserted.

33. In a fastening inserting machine, the combination of fastening forming and inserting instrumentalities with an independently reciprocating countersinking sleeve having a conical lower end, said sleeve being arranged to reciprocate to form a conical countersunk entrance for a previously formed fastening receiving hole.

34. In a fastening inserting machine, a tool operating both as a driver and as an awl, a sleeve constructed and arranged to form a 10 countersunk entrance for a fastening receiving hole formed by the tool, and means for reciprocating the tool and the sleeve in timed relation to each other.

35. In a fastening inserting machine, a tool 15 operating to form a fastening receiving hole in a work piece and for inserting a fastening in the hole, a cam, connections between the cam and the tool to cause the tool to perform its operations, a sleeve having a passage through which 20 the tool is reciprocated, and means for reciprocating the sleeve in timed relation to the operating tool to countersink the entrance of a hole in which a fastening is inserted and headed by the tool.

25 36. In a fastening inserting machine, a tool, a cam, connections between the tool and the cam to cause the tool to reciprocate to form a fastening receiving hole in a work piece and to insert a fastening in the hole, a sleeve having a passage through which the tool reciprocates, and means for reciprocating the sleeve in timed relation to the operating movements of the tool, said sleeve having a conical end which upon reciprocation of the sleeve engages the work to 30 form a countersunk entrance for the hole in which a fastening is headed by the tool during its fastening inserting stroke.

FRED N. LA CHAPELLE. 40
